UNITED STATES PATENT OFFICE.

WILLIAM CRONK, OF MONTOUR FALLS, NEW YORK, ASSIGNOR TO THE CRONK HANGER COMPANY, OF ELMIRA, NEW YORK.

PLIERS.

SPECIFICATION forming part of Letters Patent No. 632,835, dated September 12, 1899.

Application filed March 10, 1898. Serial No. 673,290. (No model.)

To all whom it may concern:

Be it known that I, WILLIAM CRONK, of Montour Falls, in the county of Schuyler, in the State of New York, have invented new and 5 useful Improvements in Pliers, of which the following, taken in connection with the accompanying drawings, is a full, clear, and exact description.

My invention relates to improvements in 10 combination pliers and staple-pullers; and the object is to provide a simple and efficient device and at the same time construct the same in such a manner that it may be easily repaired should the jaws of the staple-pulling 15 device become broken.

In the drawings hereto annexed and forming a part of this specification, Figure 1 is a perspective view of my invention. Fig. 2 is a side view of the pliers engaged with a staple 20 and in a position to withdraw the staple from a wall. Fig. 3 is an end view showing the jaws closed. Fig. 4 is an enlarged detached view of one of the jaws of the staple-pulling means. Fig. 5 is an end view of one of the 25 members of the pliers having a staple-pulling jaw riveted thereto. Fig. 6 shows a portion of one of the members of the pliers having a staple-pulling jaw secured thereto by a screw; and Fig. 7 is an end view of the same.

30 It will be apparent that my invention consists in providing pliers having either flat or round noses or pliers of any description or analogous instruments with removable staple-pulling devices or jaws, so that if said jaws are broken or injured they may be easily removed and others inserted. Heretofore the staple-pulling jaws were integral with the members of the pliers, and if the said jaws were broken the tool was worthless for the purpose of pulling staples, necessitating the purchase of another. With my improved tool it is only necessary to be provided with a few of these jaws, and when one is accidentally broken it may be easily removed and a new 45 one inserted with very little expense.

My invention, it will be seen, is combined with a device which includes several tools—namely, flat pliers, hammer, and wire-cutter. In fact, there are shown in the device in the 50 drawings a pair of hammer-faces, one on each

jaw of the pliers, and a pair of shear wire-cutters on opposite sides of the bolt or rivet. The wire-cutters are in themselves old and well known and need not be described herein in detail.

Referring specifically to the drawings, A A indicate the plier-jaws, which are flat and preferably roughened on their clamping-surfaces and tapered on their outer surfaces, as usual in flat pliers. Each jaw is provided with a flat 60 hammer-face B B, which allows the pliers to be used as a hammer whichever side is uppermost without changing its position in the hand.

C are the wire-cutters, located on each side 65 of the bolt or rivet D, by which the pliers A A, with their handles A' A', are secured together. Said cutters are each formed by a pair of recesses in the edges of the parts which coincide with each other when the jaws are open, 70 and pass each other while closing the jaws in the usual and well-known manner.

Each jaw and handle are made in one piece, the portion of the handle where it is pivoted to the other handle being recessed and interlocked with the opposite handle, the handles being crossed at their interlocking points. The cutters may be of the same size or of different sizes, and the pliers may be round-nosed pliers or otherwise shaped without departing from my invention.

On the flat outer sides of the pliers, between the rivet D and the ends of the noses, are ribs or projections b b, which extend outward at right angles to the clamping-surfaces of the 85 pliers and open and close with the pliers when operated. The clamping or gripping ends of these projections are inclined or concaved for the purpose of gripping a staple without cutting it. The projections b b are preferably 90 claw-shaped and flattened on their sides to be engaged by a wrench or other pliers when inserted or removed. Each projection b is preferably provided with a shank which is either screw-threaded or plain for extending into or 95 through the member of the pliers and securing the parts together. Holes are drilled transversely through the members of the pliers, and these are threaded when the shanks of the staple-pulling jaws are threaded, as 100

shown in Fig. 4 of the drawings. If these jaws are only applied to one side of the pliers, the shanks of the jaws may extend entirely through the members; but if applied to both 5 sides, as indicated in Figs. 2 and 3, they only extend half-way through, two shanks occupying the same hole.

Fig. 5 shows a staple-pulling projection *b*, having a plain shank *c* extending from a 10 shoulder and entirely through the member of the pliers, its end being riveted upon the opposite side. This form is cheaper than the threaded form, but is not so easily removed and inserted. When this form is applied to 15 opposite sides of the member, a pair of holes is necessary.

Figs. 6 and 7 show different views of a modification wherein the securing means for the projection is not integral therewith, but 20 formed of a separate rivet or screw *e*, which enters or extends through the member of the pliers and also through the projection or jaw *b* of the staple-puller.

In Fig. 2, *F* is a wall, and *E* is a staple fixed 25 therein and engaged by my improved pliers. By pulling the handles *A'* away from the wall

| F the staple will be withdrawn as the ends of the noses of the pliers form a fulcrum, resting as they do upon the wall above the staple.

I do not desire to be limited to the form of 30 pliers or staple-pulling jaws shown, nor to the securing means for said jaws, as it will be obvious that these may all be widely varied without departing from my invention.

Having described my invention, what I 35 claim as new, and desire to secure by Letters Patent, is—

In a tool, the combination of a pair of jaws hinged together, each provided with a suitable handle, and a pair of claw-shaped jaws 40 projecting from the sides of the first-mentioned jaws, and provided with screw-threaded shanks extending into threaded apertures in the sides of the first-mentioned jaws, substantially as described and shown. 45

In testimony whereof I have hereunto signed my name.

WILLIAM CRONK. [L. S.]
